LINE FEED MECHANISM

Berthel F. Madsen, Chicago, Ill., assignor to Teletype Corporation, Chicago, Ill., a corporation of Delaware

Application February 14, 1951, Serial No. 210,910

4 Claims. (Cl. 197—114)

1

The present invention relates to page printers and more particularly to line feed mechanisms therefor, whereby a sheet is stepped forward periodically so that a message can be typed in a plurality of lines.

The principal object of the invention is to provide a quietly and efficiently operable line feed mechanism for page printers.

Another object of the invention is to provide a line feeding arrangement wherein the feeding motion is smoothly accelerated and decelerated during each line feeding operation.

A further object of the invention is to provide a line feed mechanism comprising a gear attached to the platen, and a pair of rack members which are reciprocated alternatively by a corresponding pair of eccentric devices under the control of a movable pivotal support for said racks, whereby simple harmonic motion is imparted to said platen during each line feeding operation.

Other objects and features of the invention reside in providing a positively driven line feed mechanism which permits high speed operation without overrolling or overstepping of the platen. Moreover, the device according to the present invention does not require the heavy load of a detent to stop the platen at the end of the feeding stroke. Further, the mechanism according to the invention does not require a detent or other lock to prevent play in the platen at the time the printing operation is performed, because the rack members function to hold the platen against movement during the printing operation.

A more complete understanding of the invention may be had by reference to the following description when considered in conjunction with the accompanying drawings, wherein,

Fig. 1 is a perspective representation of the line feed mechanism according to the present invention;

Fig. 2 is an elevational view of the line feed mechanism; and

Fig. 3 is a sectional view in elevation showing the line feed operating instrumentalities.

The line feed mechanism according to the present invention is adapted to be embodied in a telegraph page printer of the type disclosed in United States Patent No. 2,505,729 granted April 25, 1950, to W. J. Zenner, which disclosure is incorporated herein by reference, and made a part hereof.

Having reference to Figs. 1, 2 and 3 of the drawings herein, the line feed mechanism of the present invention comprises a gear 11 fixedly re-

2

lated to the platen 12 of the printing machine, and a pair of drive or rack members 13 and 14. Referring to Fig. 3, the line feed clutch is indicated at 15 and may be any form of cyclically operable clutch; for example, it may be of the form shown in Figs. 31 and 32 of said Patent No. 2,505,729.

The gear 11 rotates with the platen 12 and the rack members 13 and 14 are adapted to be alternately engageable with the teeth on the gear 11, with a slight overlap of engageability being provided, so as to impart substantially uniform rotative motion to the gear 11 and platen 12. The mechanism of the present invention obviates the jerky movement inherent in pawl and ratchet mechanisms and imparts to the platen a smoothly accelerated and decelerated motion, thus simulating simple harmonic motion.

The rack members 13 and 14 are connected to eccentric 16 and 17, respectively, which are operatively related to the line feed clutch 15 (Fig. 3), and power for operating said racks is derived from the main shaft 18 through said clutch. The eccentric thus control the reciprocatory motion of the rack members 13 and 14. As shown in Figs. 1 and 2, the rack members 13 and 14 are adapted to be rocked on a movable pivot 19 comprising a roller 21 cooperable with slots 22 and 23 in said rack members 13 and 14. The friction roller 21 is carried on the vertical arm of a bell crank lever 24 pivotally mounted on a pivot stud 25 fixed to the side frame of the apparatus. The bell crank lever 24 is normally biased clockwise about pivot 25 by a spring 26 against an adjustable stop 27.

Upon rotation of the eccentric 16 and 17, a combination of rocking motion about pivot 19 and vertically reciprocating motion is imparted to the rack members 13 and 14. When the rack members 13 and 14 are rotated clockwise about the pivot roller 21 by their respective eccentric 16 and 17, the teeth on the rack members 13 and 14 will engage the teeth of gear 11. To permit the rack teeth to mesh with the gear teeth under pressure, the fulcrum pivot 21 is made movable so that slight counterclockwise movement is imparted to bell crank 24, thus increasing the tension of spring 26.

In the performance of the line feed operation, the line feed code signal is received by the selector mechanism, such as described in said Patent No. 2,505,729, to effect a setting of the code bars 28 to select the line feed function control lever 29 (similar to lever 39 shown in Fig. 29 of Patent No. 2,505,729) which through its interponent 31

3

actuates the line feed clutch release lever (not shown), similar to lever 377 shown in Fig. 15 of said Patent No. 2,505,729, which initiates a cycle of rotation of the line feed clutch 15, which, in turn, controls the rotation of the eccentrics 16 and 17. As shown in Fig. 1 the eccentrics 16 and 17 are arranged to actuate the racks 13 and 14 in an alternate manner, as described above.

As viewed in Fig. 2, the eccentrics 16 and 17 are rotative in a counterclockwise direction. When the long radius of eccentric 16 is operative to the left of the vertical center line of the shaft 18, the rack member 13 is actuated clockwise about pivot 19 to bring the rack teeth into engagement with the gear 11. The rack member 13 is also actuated downwardly to impart counterclockwise rotation to the gear 11, and hence the platen 12. Then, when the long radius of eccentric 16 is operative to the right of said vertical center line, the rack member 13 is actuated counterclockwise about pivot 19 to disengage the rack teeth from gear 11. The rack member 13 is further actuated upwardly with the teeth thereon free of the gear 11.

The same actions are imparted to the rack member 14 by the eccentric 17 except that they occur alternatively, thereby imparting smoothly accelerated and decelerated movement to the gear 11. As previously mentioned, the pivot 19 is yieldable, so that due to the pull of spring 28, the teeth on the rack members 13 and 14 are adapted to mesh with gear 11 under pressure.

Although a preferred embodiment of the invention has been disclosed and described herein, it is manifest that changes may be made in the details set forth without departing from the essentials of the invention.

What is claimed is:

1. In combination in a recorder, a platen, an instrumentality associated with said platen, a pair of drive members cooperable with said instrumentality, spring loaded means for mounting said drive members for pivotal and reciprocative movements, and a pair of eccentric means individually associated with said drive members to actuate said members, said pair of means offset angularly with respect to each other, whereby said drive members are engageable alternatively

4
with said instrumentality to impart rotation to said platen.

2. In combination in a recorder, a platen, a gear associated with said platen, a pair of rack members cooperable with said gear, spring loaded means for mounting said rack members for pivotal and reciprocative movements, and a pair of eccentric means individually associated with said rack members to actuate said members, said pair of means offset angularly with respect to each other, whereby said rack members are engageable alternatively with said gear to impart rotation to said platen.

3. In combination in a recorder, a platen, an instrumentality associated with said platen, a pair of drive members cooperable with said instrumentality, spring loaded means articulated to said pair of drive members in a manner to enable pivotal and reciprocative movement of said drive members, and a pair of eccentric means individually associated with said drive members to actuate said members, said pair of means offset angularly with respect to each other, whereby said drive members are engageable alternatively with said instrumentality to impart rotation to said platen.

4. In combination in a recorder, a platen, an instrumentality associated with said platen, a pair of drive members cooperable with said instrumentality, each of said members being provided with a slotted portion, yieldable fulcrum means cooperable with said slotted portions for facilitating pivotal and reciprocative movements of said pair of drive members, and a pair of eccentric actuating means individually associated with said drive members and offset angularly with respect to each other, whereby said drive members are rendered engageable alternatively with said instrumentality to impart rotation to said platen.

BERTHEL F. MADSEN.
